UNITED STATES PATENT OFFICE.

GEORGE A. YANOCHOWSKI, OF CHICAGO, ILLINOIS, AND HARRY E. HERSEY, OF WHITEWATER, KANSAS, ASSIGNEES TO AUTOMATIC ELECTRIC COMPANY, OF CHICAGO, ILLINOIS, A CORPORATION OF ILLINOIS.

SEMI-AUTOMATIC TELEPHONE SYSTEM.

1,317,190.

Specification of Letters Patent. Patented Sept. 30, 1919.

Application filed November 25, 1914. Serial No. 874,054.

To all whom it may concern:

Be it known that we, GEORGE A. YANOCHOWSKI and HARRY E. HERSEY, both citizens of the United States of America, and 5 residents of Chicago, Cook county, Illinois, and Whitewater, Butler county, Kansas, respectively, have invented certain new and useful Improvements in Semi-Automatic Telephone Systems, of which the following 10 is a specification.

Our invention relates to telephone systems and is particularly applicable to manual telephone systems. Among the objects of our invention are the following:

- 15 To provide means whereby when a subscriber removes his receiver he immediately supplies a guarding potential to the multiple jacks of his line; to provide means for automatically giving a calling subscriber a signal as soon as the operator disconnects from his line to indicate to him that he should hang up his receiver; to provide means whereby a B operator can automatically give an A operator a disconnect signal by merely dropping the calling plug; to provide means for automatically giving one operator a disconnect signal from another operator's position by automatically varying the resistance of the talking circuit between the two cords; and to provide other details and features of improvement and combination tending to increase the efficiency and serviceability of a telephone system. Means for accomplishing the foregoing and other useful ends are hereinafter set forth and claimed.
- 20
- 25
- 30
- 35

In the accompanying drawings Figures 1 and 2 show a complete connection in a manual telephone system embodying the 40 principles of our invention.

Fig. 1 shows the manual substation T, an answering jack equipment J, multiple jacks M and an operator's cord circuit S.

Fig. 2 shows a manual substation T', 45 answering jack equipment J, multiple jacks M and a B-operator's cord circuit I.

The manual substation T is an ordinary common battery manual telephone comprising the usual receiver 2, transmitter 3, 50 ringer 4 and condenser 5. The substation T' is similar to the substation T.

The answering jack equipment J consists of the usual line relay 6, cut-off relay

7, line lamps 8 and an answering jack 9. And in addition there is provided the slow 55 acting relay 10. The answering jack equipment J' is similar to that shown at J except that the relays 6 and 10 are replaced by the one double wound relay 11^a. The relay 11^a is so constructed and adjusted 60 that when a circuit is closed through its left hand winding and not through its right hand winding the armature 93 alone will be attracted.

The A operator's cord circuit S is a well 65 known type of cord circuit comprising the usual answering and calling plugs P and P', respectively, inductively connected together through the medium of a repeating coil R. The usual supervisory relays 11 70 and 12 are included in the sides of the cord circuit for controlling the supervisory lamps 13 and 14.

The B-operator's cord circuit I comprises the plug P², the supervisory lamp 15 and 75 relays for controlling the same. At 16 is shown a plug seat switch whose springs are separated when the plug P² is in its seat.

For the purpose of supplying battery 80 current for operating the apparatus and for talking purposes, there is shown the battery B, having one terminal grounded at G. The busy signaling machines Q' and Q² as represented herein, comprise an in- 85 duction coil or transformer, the primary winding of which is included in a local circuit with a battery and an interrupter. Through the medium of this interrupter an interrupted current is supplied to the 90 primary winding, which induces an alternating current in the secondary winding, whereby when said winding is connected with the subscribers line, a buzzing sound is heard in the receiver.

A general description of the apparatus having been given, it will now be explained how connection can be established between the line of substation T and the line of a called substation T'. 95

Upon the removal of the receiver at the calling substation a circuit may be traced from ground G¹ through springs 17 and 18, to and through substation T, springs 19 and 20 and the relay 6 to battery B. The 100 relay 6, upon energizing, places ground

from G^2 upon the bush of all the multiple jacks associated with the line of substation T, and in addition closes a circuit from ground G^3 , through springs 21 and 22, lamp 8, springs 23 and 24 to battery B. The operator upon seeing the lamp 8 glowing, knows that a connection is desired and thereupon inserts the plug P into the jack 9. A circuit may now be traced from ground G^4 through relay 25, sleeve of plug P and bush of jack 9, relay 7, relay 10 to battery B. The relays 25, 7 and 10 energize over the above circuit, the relay 7, upon energizing, removes the line relay 6 from the line and extends the connection to the cord circuit S. The relay 10, upon energizing, removes ground G^3 from the circuit of lamp 8. The relay 25, upon energizing, closes the circuit of lamp 13 at the springs 25^a, but this is without effect as the said circuit is opened at the springs 27, as will be hereinafter explained. Upon the energization of relay 7 a circuit may be traced from ground G^5 through winding 28 of repeating coil R tip of plug P and of jack 9, springs 19 to and through substation T, springs 18 and 18^a, ring of jack 9 and of plug P, relay 11, winding 29 of repeating coil R to battery B. The relay 11, upon energizing, opens the circuit of the lamp 13 at the springs 27. The A-operator now depresses the key K, thereby cutting her talking set across the calling line, and converses with the calling subscriber. Upon learning the number of the called subscriber the A-operator depresses the order wire key K' and repeats the number to the B-operator, the B-operator then assigns the trunk to be used.

The B-operator upon receiving an order, raises the plug P^2 , associated with the trunk she has assigned to the A-operator, from its plug switch seat 16 and touches the bush of the jack of the called line with the tip of the said plug. If the line is idle, the B-operator then inserts the plug P^2 into the jack M and in so doing closes a circuit from ground G^6 through relay 30, sleeve of plug P^2 and bush of jack M, springs 31, the two windings of relay 11^a in series to battery B. The relay 11^a, upon energizing, removes the line relay 32 from the called line. The relay 30, upon energizing completes the talking circuit through the cord circuit I. Upon the removal of the plug P^2 from the plug seat switch 16, a circuit may be traced from ground G^{16} through springs 16, relay 35 to battery B. The relay 35, upon energizing, closes a circuit through the lamp 15 which is without effect at this time, since the said lamp will immediately be extinguished as hereinafter explained.

The A-operator, upon being assigned a trunk, inserts the plug P' into the jack 33, associated with the assigned trunk. A circuit may now be traced from ground G^7

through resistance 36, bush of jack 33 and sleeve of plug P', relay 37 to battery B. The relay 37, upon energizing, closes a circuit from ground G^8 through springs 38, lamp 14, springs 39 to battery B. The glowing of lamp 14 informs the A-operator that the called party has not answered. As a further result of the insertion of the plug P' into the jack 33, another circuit may be traced from ground G^9 through winding 34 of repeating coil R, tip of plug P' and of jack 33 conductor 90, resistance 40, relay 41, conductor 91, ring of jack 33 and of plug P', relay 12, winding 42 of repeating coil R to battery B. The resistance 40 is high enough that relay 12 will not operatively energize over the above circuit, the relay 41, however, energizes and opens the circuit of the lamp 15 at the springs 43.

Returning to the operation of the B-operator's cord circuit Fig. 2 it will be seen that upon the energization of the relay 30 a circuit is closed from ground G^9 through interrupter 44, springs 45, springs 46, and ringer relay 47 to battery B. The ringer relay 47 energizes intermittently due to the interrupter 44 and operates to disconnect the called line from the cord circuit and bridge the ringing current generator R in series with battery B across the called line. The circuit may be traced from ground G^{10} through springs 48 and 48^a, springs 49 and 50, tip of plug P^2 and of jack M, springs 51 and 52, through ringer and condenser at substation T' springs 53 and 54 ring of jack M and of plug P^2 , springs 55 and 56, upper winding of relay 57, generator R, and through battery B to ground G. The ringer at substation T' will be energized by the ringing current, but the relay 57 is so adjusted that it will not respond to the said ringing current. Upon the response of the called subscriber a path for direct current will be formed at the substation T' whereupon the relay 57 will become energized. The relay 57, upon energizing, opens the circuit of the ringer relay at the springs 45, in addition forms a locking circuit for itself from ground G^{11} through the lower winding of relay 57, springs 58, springs 59 to battery B.

Upon the deenergization of ringer relay 47 battery and ground are supplied to the called line through the relays 60 and 61. The relay 60, upon energizing, shunts the resistance 40 at the springs 62, this increases the flow of current in the trunk to such an extent that the relay 12 becomes energized and opens the circuit of the lamp 14. The extinguishing of the lamp 14 notifies the A-operator that the called subscriber has answered.

Upon the completion of the conversation the restoring of the receiver at the calling substation opens the circuit of the relay 11. The relay 11, upon deenergizing, closes a cir-

cuit from ground G^{12} through springs 27, springs 25^a and lamp 13 to battery B. Thus causing said lamp 13 to glow. The restoring of the receiver at the called sub-
 5 station opens the circuit of the relay 60, which, upon deenergizing, removes the shunt from around the resistance 40. This added resistance in the trunk causes the relay 12 to release its armature thus again closing
 10 the circuit of the lamp 14. The A-operator, upon seeing both the lamp 13 and the lamp 14 lighted knows that a disconnect is desired and forthwith removes the plugs P and P' from their respective jacks. The
 15 removal of the plug P' from the jack 33 opens the circuit of relay 41, which, upon deenergizing, closes a circuit from ground G^{13} through springs 43, lamp 15, springs 59 to battery B. The glowing of the lamp 15
 20 informs the B-operator that the A-operator has taken down the connection, whereupon the B operator removes the plug P² from the jack M. The restoring of the plug P² to the plug seat switch 16 opens the circuit
 25 of the relay 35. The relay 35 upon deenergizing opens the circuit to the lower winding of relay 57.

It having been explained how a connection can be established between a calling
 30 and a called subscriber and how the same is released, it will now be explained how a connection is prevented from being made with a busy line and how the connection is then taken down and the calling subscriber given
 35 the busy signal from his answering jack equipment. If the called line should be busy, there will be a ground potential upon the bush of all the multiple jacks associated with that line. When the B-operator
 40 touches the tip of the plug P² to the bush of a busy multiple jack, a circuit will be formed from ground potential at the multiple jack through tip of plug P², springs 50 and 63 and tertiary winding 64 of induction
 45 coil to battery B. This flow of current will cause a click in the B-operator's receiver which will inform her that the called number is busy, whereupon she returns the plug P² to its plug seat switch 16, thus opening
 50 the circuit of the relay 35. The relay 35, upon deenergizing, closes a circuit from ground G^{14} through interrupter 65, springs 66, springs 67, relay 68 to battery B. The relay 68 energizes intermittently, due to the
 55 interrupter 65 and operates to periodically shunt the resistance 40 at the springs 69. This shunting of the resistance 40 causes the lamp 14 to be intermittently extinguished thus informing the A-operator that the
 60 called number is busy. The A-operator then removes the plugs P and P' from their respective jacks. The removal of the plug P from the jack 9 opens the circuit of the cut-off relay 7, which, upon deenergizing,
 65 closes a circuit from ground G', through

springs 17 and 18, to and through substation T, springs 19 and 20 and relay 6 to battery B. The relay 6, upon energizing, closes a circuit from ground G^2 through springs 70 and 71, springs 72, relay 10 to battery B. 70 The relay 10, being slow acting, did not deenergize immediately upon the withdrawal of the plug P, but remained energized long enough for the above traced circuit to be formed, after which it of course locks up. 75 Another circuit is now formed from ground G^{15} through interrupter 73, secondary of busy machine Q', springs 74, springs 75 to and through the substation T, springs 18 and 17 to ground G'. The calling subscriber 80 upon hearing the busy tone will know that the called number is busy and will then return his receiver to the receiver hook, thereby causing the deenergization of line relay 6, which in turn allows the relay 10 to deenergize. It will be seen that as long as the calling subscriber is receiving the busy tone there will be a guarding potential from ground G^2 upon all of the multiple jacks associated with that line. 85

It will be seen therefore that we have provided an improved arrangement whereby as soon as a subscriber's line relay energizes a guarding potential is applied to the multiple jacks M so as to make the calling line 95 busy even before the operator answers. We have also provided an improved arrangement whereby the line relay of the subscriber controls the signal for the operator and also controls a signal for the subscriber to indicate to him that he should hang up his receiver and call again. We also provide means whereby the B operator through the medium of a plug seat comprising the plug 16 is enabled to give the A operator automatically a busy flash signal by varying the resistance on the line between the two cords. The means for accomplishing this comprises, of course, the relay 68 and the interrupting machine 65. 100 105 110

Therefore it will be seen that we have provided an improved system in which the efficiency of the equipment is increased by simplifying the matter of signaling.

What we claim as our invention is:

1. In a telephone system, an A trunk, a relay in said trunk and a signal controlled thereby, a B trunk terminating in a plug, means for connecting said A and B trunks to extend the conductors of a talking circuit 120 to said plug, a circuit controlled by said plug, means for automatically varying the resistance of the said talking circuit comprising a magnet, said magnet located in the said plug controlled circuit, means for energizing said magnet when the plug is raised to prevent the variation of said resistance, and means for breaking the circuit of said last magnet when the plug is replaced for deenergizing said magnet whereby the said re- 125 130

sistance may be varied, said relay responsive to said variation in the talking circuit to operate the signal.

2. In a telephone system, an A cord, a talking circuit connecting the two, a signal at the A cord, a plug seat switch at the B cord, means controlled by the A operator for operating said signal, means controlled by the called subscriber for retiring said signal, and means for intermittently operating said signal, said last means controlled by the B operator's plug seat switch.

3. In a telephone system, an A cord, a talking circuit connecting the two, a signal at the A cord, a plug seat switch at the B cord, means controlled by the A operator for operating said signal, means controlled by the called subscriber for retiring said signal, and means for varying the resistance of said talking circuit to intermittently operate said signal, said last means controlled by the B operator's plug seat switch.

4. In a telephone system, an A cord, a B cord, a talking circuit connecting the two, a signal at the A cord, a plug seat switch at

the B cord, means controlled by the A operator for operating said signal, electromagnetic means controlled by the called subscriber for retiring said signal, and electromagnetic means for intermittently operating 30 said signal, said last means controlled by the B operator's plug seat switch.

5. In a telephone system, an A cord, a B cord, a talking circuit connecting the two, a signal at the A cord, a plug seat switch at 35 the B cord, means controlled by the A operator for operating said signal, electromagnetic means controlled by the called subscriber for retiring said signal, and electromagnetic means for varying the resistance 40 of said talking circuit to intermittently operate said signal said last means controlled by the B operator's plug seat switch.

Signed by us at Chicago, Cook county, Illinois, this 11th day of November, 1914.

GEORGE A. YANOCOWSKI.

HARRY E. HERSHY.
